UNITED STATES PATENT OFFICE.

JAMES H. ROBINSON, OF LEWISTON, IDAHO.

SPUR.

SPECIFICATION forming part of Letters Patent No. 625,063, dated May 16, 1899.

Application filed April 27, 1898. Serial No. 679,039. (No model.)

To all whom it may concern:

Be it known that I, JAMES H. ROBINSON, a citizen of the United States, residing at Lewiston, in the county of Nez Perces and State of Idaho, have invented a new and useful Spur, of which the following is a specification.

My invention relates to riding-spurs, and has for its object to generally improve, simplify, and cheapen their construction.

With this object in view my invention consists in a spur the supporting-frame of which is formed of a single piece of metal cut or stamped from a sheet and bent to form.

My invention further consists in the improved construction, arrangement, and combination of parts hereinafter fully described and afterward specifically pointed out in the appended claims.

In order to enable others skilled in the art to which my invention most nearly appertains to make and use the same, I will now proceed to describe its construction and operation, reference being had to the accompanying drawings, forming part of this specification, in which—

Figure 1 is a rear under side perspective view of a spur constructed in accordance with my invention. Fig. 2 is a longitudinal vertical section through the same. Fig. 3 is a view of the blank from which the body of my spur is formed. Fig. 4 is a plan view of the heel-plate.

Like letters of reference mark the same parts wherever they occur in the different figures of the drawings.

Referring to the drawings by letters, A indicates a band which is intended to surround the heel, said band being formed in one piece, with upright bars B B at the front and C at the rear, said upright bars being bent to form

loops B' and C' to receive a strap D to be passed over the instep in securing the spur to the boot, said strap being adapted to be tightened and secured by means of a buckle E at one end.

Tangs F, formed on the lower edge of the band A at the rear curves, and a flange G, formed on its front face, are bent inward at substantially right angles to the band to receive and support a heel-plate H.

Calks I I are formed at the forward corners of the band A, and a calk J is formed at the rear portion of said band, the purpose of said

calks being to support the heel-plate above the ground and prevent said plate wearing away.

K indicates a curved plate adapted to fit the back of the heel of the boot. Upon the outside of this curved plate is secured a loop or bracket L, which provides an opening to receive the uprights C, a round bar M, projecting backward and slightly downward, being secured to the bracket L and provided at its rear with bifurcated or forked end N, in which is pivotally mounted the rowel O.

In the manufacture of my improved spur the blank, as shown in Fig. 3, is stamped or cut from a sheet of flexible metal, the uprights B B and C lying at right angles to the band A, and the tangs F F, flange G, and calks I I and J being formed on the opposite side of the blank and afterward bent on the dotted lines P. The heel-plate H is also stamped out of a single piece of metal. In attaching the spur to the heel the frame is slipped over the heel in the manner usual, with the bottom of the heel resting upon the heel-plate H, the upright C standing vertical in the rear of the heel and the uprights B B standing vertically at the sides of the heel, when the whole device may be firmly held upon the heel by securing the strap D over the instep.

While I have illustrated and described what I now consider to be efficient means for carrying out my invention, I do not wish to be understood as limiting myself to the exact details of construction shown and described, but hold that such slight changes or variations as might suggest themselves to the ordinary mechanic would properly fall within the limit and scope of my invention.

Having thus fully described my invention, what I claim as new, and desire to secure by Letters Patent of the United States, is—

1. The combination with the supporting-frame, consisting of the band, A, adapted to encircle the heel, the uprights, B, B and C, adapted to rest against the sides and rear of the heel, tangs, F, F, and flange, G, projecting from the lower edge of the band and bent inward at right angles, and the heel-plate, H, fitted within the band, A, and resting upon the tangs and flange, substantially as described.

2. The herein-described frame for spurs, consisting of the band, A, adapted to encircle the heel, the uprights, B, B and C, adapted to lie against the sides and rear of the heel and formed at their upper ends into loops, B', B' and C, to receive a securing-strap, calks, I, I and J, projecting below the band and forming part thereof, tangs, F, F, and flange, G, projecting below the band, formed integrally therewith and bent inward at right angles thereto, and the heel-plate, H, seated inside of the band and supported upon the tangs and flange, substantially as described.
3. The combination with the supporting-frame of a riding-spur, provided with a rear

upright, C, of a curved plate, K, adapted to fit against the rear of the heel inside of said upright, the bracket or loop, L, secured on the rear of said curved plate and passing around the upright, C, the bar, M, secured on the rear of the bracket or loop, L, projected rearward and downward and having its rear end bifurcated, and the rowel, O, pivotally mounted between the forks of said bifurcated end, substantially as described. 20

JAMES H. ROBINSON.
